UNITED STATES PATENT OFFICE

RONALD PURVIS JAMESON, OF CHRISTCHURCH, NEW ZEALAND, ASSIGNOR TO THE VIGILANT AUTOMATIC FIRE ALARM COMPANY LIMITED, OF CHRISTCHURCH, NEW ZEALAND, A COMPANY OF NEW ZEALAND

ELECTRICAL FIRE ALARM

Application filed October 27, 1931, Serial No. 571,389, and in New Zealand July 10, 1931.

This invention relates to electrical fire alarm systems in which thermostatic circuit controlling devices are adapted to operate a closed circuit and an open circuit by means of a system of yieldable contacts within the circuit closing device, and particularly to the kind in which one of the yieldable contacts normally completes the closed circuit but which, upon release, will break such closed circuit and operate to close a normally open circuit, as in the pending application Number 323,083 filed 1st December 1928.

The object of the present invention is to improve and simplify the construction of the thermostatic circuit controlling device and render it more efficient. A further object is to enable the breaking of the closed circuit to operate a transmitting device and cause a message to be transmitted to an alarm station, or where desired, and, at the same time, to enable the closing of the open circuit to send a similar message by another or the same transmitter, thereby providing a double message, but a mere fault or a failure of one of the circuits, such as a broken line, will only convey a single message, thereby indicating that there is a fault in the system or only a partial operation of the thermostatic device.

According to the present invention, a yieldable contact is fixed at one end in a terminal post to which one line of the closed circuit is connected. The other end of this yieldable contact is such that it would normally spring away or disconnect from a contact post to which the other line of a closed circuit is connected. This yieldable contact, however, is caused to bear firmly against its contact post by means of a rod or pin connected to the yieldable contact and passing through the casing of the device and normally held at that position through the intervention of a fusible metal, or other suitable substance fusible by heat, which, upon the fusing or melting thereof, will release the rod and permit the yieldable contact to resume its normal position under its own tension and break contact with its contact post, thereby breaking the closed circuit. A further terminal post, insulated from the two previous posts, has the lines of the open circuit connected thereto and this post contains a yieldable contact which extends to a position where it will normally lie between the end of the closed circuit yieldable contact and a fixed contact projecting from a

post metallically connected with the contact post of the closed circuit.

The invention will be described with the aid of the accompanying drawing, wherein:—

Figure 1, is a cross sectional elevation 60 through the thermostat.

Figure 2, is a cross section of the thermostat viewed in the direction of the arrow in Figure 1, the cut being along line A—A Figure 1. 65

Figure 3, is a sectional plan of the portion carrying the contacts and taken along line B—B, Figure 2.

Figure 4, is a side view of a detail.

Figure 5, is a sectional elevation through 70 the rod and fusible nuts, but drawn to a scale twice that of the previous figures.

Figure 6, is a cross section on line C—C, Figure 5.

Referring to the drawing, a base 1, preferably of a suitable electrical insulating material, has depending from it a flange or wall 2, a central opening 3 in the base being screw threaded upon the end of conduit tubing 4. An opening 5 in the wall 2 is provided to 75 permit the wiring to pass to the left or rear side of the wall 2, which is strengthened in its attachment to the base 1 by buttress pieces 7. Mounted on the wall 2 is a terminal post 8 to which one line of the closed circuit would 80 be connected. In this post, a yieldable contact consisting of a metallic metal strip 9 is fixed and is such that its other end would normally spring away from a contact 10 mounted in a contact fork 11 fixed in the wall 2, to 85 which fork the other line of the closed circuit is connected by its terminal screw 12.

Another terminal post 13 is mounted in the wall 2 and insulated from the post 8 by reason of the material of the wall. This post carries 90 a yieldable contact formed of a strip of metal 14 which extends to a position where it will normally lie between the ends of the closed circuit yieldable contact 9 and a contact piece 15 carried in the contact fork 11. The lines 100 of the open circuit are attached to the terminal screw 16 of the post 13. The yieldable contact 9 is caused to bear firmly against its contact post 10 (see Figures 3 and 5) by means of a rod or pin 18 connected to the yieldable contact by passing through a slot 19 therein having a pin 20 bearing against a washer 21 interposed between the pin and the contact. This rod passes through a guide sleeve 22 adjustably threaded into a post 24 105

fixed in the wall 2. This retaining rod is held in an adjusted position by a double nut consisting of an inner nut 25 screwed on the threaded end of the retaining rod 18. A hollow shell 26 forms the external part of the double nut and is adhered to the inner nut 25 by having a space 27 between the two nuts filled with a fusible metal in order to adhere the two parts together, the edge of this outer nut or shell bearing on the sleeve 22. By rotating the nut, the contact 9 is caused to bear upon the contact 10 and retained in such contact position by the outer nut 26 being supported on the sleeve 22. When, however, the fusing of the metal takes place, the inner nut 25 is freed or loosened from the outer nut and the rod, under the tension of the yieldable contact 9, will draw the inner nut into the space 28 in the sleeve 22. The outer end of the nut 25 may be flared, as shown in Figure 5, and the interior of the shell 26 formed slightly larger at its inner end than at its outer end.

When the fusing takes place, and the retaining rod 18 is released as above described, the yieldable contact 9 will move away from the contact 10, and will at first break the normally closed circuit existing between the fork 11 and the terminal 8 through wires 28 and 29 and will contact with the yieldable contact 14 and complete the normally open circuit from wire 28 through the contacts 9 and 14 to the terminal post 13, to which an open circuit line 30 is connected.

The release of the closed circuit contact 9, when sufficiently free by the fusing of the metal in the space 27, will also move the second contact 14 and cause it to contact with the contact piece 15 of the fork 11 and again bridge the lines of the closed circuit between the post 8 and the fork 11 to which the wire 29 is connected, thus again causing the latter circuit to function. Also, when the contact 14 makes contact with the contact piece 15, a further open circuit is completed from wire 29 through strip 14 to a wire 32, also attached to terminal screw 16 of the post 13, thus providing two alternative paths for the open circuit, one path being through the wire 28, post 8, strip 9, strip 14, post 13 and wire 30, while the other path is through wire 29, post 11, strip 14, post 13 and wire 32. Two contact points 31 and 32 on the strips 9 and 14 ensure a good contact between the strips 9 and 14.

As in the previous devices using this form of circuit, the opening of the closed circuit may give preliminary alarms, and by the closing of the open circuit by the bringing together of the two yieldable contacts 9 and 14, a transmitting device may be operated for sending a signal to a fire brigade station, and the remaking of the closed circuit puts the fire alarm system again into action for the remaining thermostats in the same lines.

What I claim is:—

1. In electrical fire alarm systems, a thermostatic switch device including a rigid part, a yieldable contact and other contacts associated therewith, a member controlling said yieldable contact, adjustable retaining means upon the end of said member to adjust said yieldable contact and held against the rigid part of the device, said retaining means formed of two parts, one part prevented from inward movement by the rigid part of the device, the other part adjustably joined to said member, fusible metal interposed between the two parts, said other part moving in relation to the first part and permitting said member to move inward under tension of the yieldable contact when the fusible metal is fused due to heating. 70

2. In electrical fire alarm systems, a thermostatic switch device including a casing, a yieldable contact and other contacts associated therewith, a sleeve fixed in the casing of the device and rigid therewith, a member consisting of a rod pivotally attached at one end to the yieldable contact and guided in said sleeve, two-part retaining means adjustable on the end of said rod, fusible metal interposed between the two parts of the retaining means, one part of said retaining means bearing against the end of said sleeve, and the other part threadably connected to said rod and free to move in relation to the first part under tension of the yieldable contact upon the fusing of the fusible metal interposed between the two parts of the retaining means. 80

3. In electrical fire alarm systems, a thermostatic switch device including a casing having a rigid part, a yieldable contact and other contacts associated therewith, a member connected at one end to said yieldable contact, a nut screwed upon the other end of said member, said nut formed of two parts, a fusible metal holding the nut parts together, one part held against a rigid part of the casing and the other part free to move inwardly under tension of the yieldable contact upon the fusing of the metal retaining the two parts of the nut together. 90

4. In the thermostatic device as claimed in claim 10, a sleeve fixed in the casing of the device, said member in the form of a rod pivotally attached at one end to the yieldable contact and passing through said sleeve, one part of said nut formed of an inner nut screwed upon the other end of said rod, the other part of said nut formed of an outer shell and held to the first part by the fusible metal and bearing upon the end of the sleeve, said inner nut free to move through the outer shell under tension of the yieldable contact upon the fusing of the metal retaining the two parts of the nut together. 100

In testimony whereof, I have signed my name to this specification.

RONALD PURVIS JAMESON.
